COLLAPSIBLE ANCHOR

Hans Buch and John Eugene Harig,
Atlantic City, N. J.

Application October 23, 1934, Serial No. 749,646

4 Claims. (Cl. 114—208)

This invention relates to a collapsible anchor, the general object of the invention being to provide means whereby both the flukes and the stock can be collapsed so that the anchor will occupy but little space when not in use and which can be collapsed when in use so that it can be readily lifted without danger of fouling.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:

Fig. 1 is a longitudinal sectional view through the anchor.

Fig. 2 is a section on line 2—2 of Fig. 1.

Fig. 3 is an elevation.

Fig. 4 is a view taken at right angles to Fig. 3 and showing the lower part in section.

Fig. 5 is a section on line 5—5 of Fig. 4.

Fig. 6 is a view of the lower part of the shank and showing how the ring is slidably arranged thereon.

Fig. 7 is a perspective view of one of the guards.

In these drawings, the numeral 1 indicates the shank of the anchor which has its lower end reduced and of forked construction, the prongs of this forked part being shown at 2. Each prong has a longitudinally extending slot 3 therein and the lower portion of the shank is formed with the lower large chamber 4 which opens out into the space between said prongs and with a smaller upper chamber 5 which opens out into the top of the chamber 4, a bore 6 extending from the top of the upper chamber 5 into a chamber 7 formed in an enlarged part of the top of the shank. The pair of flukes is shown at 8 and the inner end of each fluke has an upright head 9 thereon which is of forked shape with the space between the prongs tapering inwardly as shown in Fig. 1. These heads overlap and a pivot pin 10 passes through the heads where they join the flukes and through the lower ends of the prongs, the holes in the prongs for this pin being shown at 11 in Fig. 6 and this pin also passes through the lower end of a pair of channel-shaped guards 12 which provide a space between themselves and the prongs 2 for a sliding collar 13 which carries a pin 14 which passes through the slots 3 in the prongs and also through a wedge member 15 which is slidably arranged in the chamber 4 and

is adapted to engage the wedge-shaped spaces formed by the prongs of the heads 9 to hold the flukes in operative position. A rod or cable 16 has one end attached to the wedge-shaped member 15 and said rod or cable passes through the chambers 4 and 5 and through the bore 6 and through the upper chamber 7 and through a hole in the top wall of the chamber 7, a ring 17 being attached to the upper end of the rod or cable. A spring 18 is coiled around a part of the rod or cable and is located in the chambers 4 and 5 and tends to press the wedge-shaped member downwardly. As will be seen when the wedge-shaped member is in its lowermost position, it will engage the wedge-shaped spaces formed by the prongs of the heads 9 of the flukes and as the collar 13 is connected with the wedge-shaped member 15 by the pin 14, this collar will also be moved downwardly so as to fit around the heads 9 and thus the flukes are locked in operative position as shown in Figs. 1 and 3. The guards 12 protect the collar 13 and a slot 12' is formed in each guard for permitting escape of any water collecting in the spaces between the guards and the lower part of the shank. These guards are connected with the shank at their upper ends as shown at 19 in Figs. 3 and 4. Thus, it will be seen that by pulling upwardly upon the cable or rod 16, the wedge-shaped member 15 and the collar 13 are raised so as to release the heads 9 of the flukes 8 so that these flukes can drop into the dotted line position shown in Fig. 1 which will enable the anchor to be readily lifted and eliminate fouling of the anchor.

We also provide means for collapsing the stock 20 by making the stock in two sections with the inner ends of the sections provided with heads 21, each head having a tapered recess 22 therein for receiving a wedge-shaped member 23 slidably arranged in the chamber 7 and connected by upper and lower collars 24 with the cable or rod 16. The wedge-shaped member has a pin 25 passing therethrough, the ends of which enter elongated slots 26' in the enlarged upper end of the shank and each head 21 of the stock is pivoted in the lower part of the chamber 7 by a pin 26. Thus when the rod or cable 16 is moved downwardly by the spring 18 to lock the flukes in operative position, the wedge-shaped member 23 is moved downwardly to lock the sections of the stock in operative position but when the cable or rod 16 is moved upwardly, the wedge-shaped member is moved upwardly so that the sections of the stock can move to the dotted line position shown in Fig. 2 while the flukes

move to the dotted line position shown in Fig. 1.

An eye-carrying part 28 is formed at the upper end of the shank to receive the anchor chain and the outer end of each fluke is of the substantially triangular shape shown at 28 in Fig. 2 and provided with the points 30 at its front. This end of the fluke insures the anchor against dragging on almost any sort of a bottom.

It is thought from the foregoing description 10 that the advantages and novel features of the invention will be readily apparent.

It is to be understood that changes may be made in the construction and in the combination and arrangement of the several parts, provided 15 that such changes fall within the scope of the appended claims.

We claim:

1. An anchor of the class described comprising 20 a shank having a forked lower end, the prongs of the forked end having longitudinally extending slots therein, a pair of flukes having heads at their inner ends, each head being of forked construction, means for pivoting the inner ends of the flukes between the prongs of the forked 25 lower end, a collar slidably arranged on the prongs and engaging the heads when in lowered position, a plunger slidably arranged in the lower part of the shank for engaging the spaces between the prongs of the heads for holding the 30 flukes in operative position, a pin passing through the plunger, through the slots in the prongs with its ends connected with the collar, a member passing through the shank and connected with the plunger and spring means for holding the plunger in lowered position.

2. An anchor of the class described comprising 35 a shank having a forked lower end, the prongs of the forked end having longitudinally extending slots therein, a pair of flukes having heads 40 at their inner ends, each head being of forked construction, means for pivoting the inner ends of the flukes between the prongs of the forked lower end, a collar slidably arranged on the prongs and engaging the heads when in lowered 45 position, a plunger slidably arranged in the lower part of the shank for engaging the spaces between the prongs of the heads for holding the flukes in operative position, a pin passing through the plunger, through the slots in the prongs with

its ends connected with the collar, a member passing through the shank and connected with the plunger and spring means for holding the plunger in lowered position, and channel-shaped guards connected with the lower end of the shank and partly closing the collar.

3. In an anchor of the class described, a shank having a chamber in its upper part, a pair of stock sections, each having a depending head on its inner end, the heads overlapping and located in the chamber when the stock sections are in horizontal position, a pivot pin passing through the lower parts of the two heads into proportions of the shank, the upper end of the heads having recesses which are in alignment with each other when the stock sections extend at right angles to the shank, a plunger which normally fits in the recesses in the head for holding the stock sections in operative position, and means for raising the plunger out of the recesses to permit the stock sections to swing downwardly.

4. An anchor of the class described comprising a shank having chambers in the upper and lower end parts, the lower chamber opening out through the lower end of the shank, a pair of flukes each having an upwardly extending head at its inner end, the heads overlapping and located in the lower chamber when the flukes are in operating position, a pivot pin passing through the lower parts of the two heads and the parts of the shank, the upper ends of the heads having recesses therein which align with each other when the flukes are in operating position, a plunger in the lower chamber fitting in the recesses for holding the flukes in operative position, a pair of stock sections each having a depending head on its inner end, a pivot pin passing through the lower ends of said heads into the walls of the upper chamber, the upper ends of said heads having recesses therein, a plunger fitting in the last mentioned recesses to hold the stock sections in operative position, and means passing through the shank and connecting the two plungers together, whereby upon pulling such means upwardly the two plungers are moved 45 out of the recesses to permit the flukes and the stock sections to swing downwardly.

HANS BUCH.
JOHN EUGENE HARIG.
